UNITED STATES PATENT OFFICE.

JAMES TROTTER, OF CHICAGO, ILLINOIS.

AUTOMATICALLY-ADJUSTABLE EXHAUST-NOZZLE FOR LOCOMOTIVE-ENGINES.

1,390,401.

Specification of Letters Patent. Patented Sept. 13, 1921.

Application filed November 22, 1920. Serial No. 425,695.

To all whom it may concern:

Be it known that I, JAMES TROTTER, a citizen of the United States, residing at Chicago, in the county of Cook and State of Illinois, have invented certain new and useful Improvements in an Automatically-Adjustable Exhaust-Nozzle for Locomotive-Engines, of which the following is a specification.

10 This invention relates to improvements in automatically adjustable exhaust nozzle for engines, especially locomotive engines, and one of the objects of the invention is to provide improved means for controlling automatically the back pressure in the exhaust cavities of the valves.

15 A further object is to provide improved means for automatically regulating the velocity of the exhaust steam out of the nozzle to control the draft on the fire by varying the size of an annular opening within the nozzle.

20 A further object is to provide an improved structure of this character embodying a floating, substantially cone shaped member or element operating in the exhaust nozzle and which element is controlled in its movement by the action or pressure of the exhaust steam thereupon, and also embodying means whereby the weight of the floating element may be varied at will to alter or vary the pressure necessary to actuate the floating element.

25 To the attainment of these ends and the accomplishment of other new and useful objects as will appear, the invention consists in the features of novelty in substantially the construction, combination and arrangement of the several parts hereinafter more 30 fully described and claimed and shown in the accompanying drawing illustrating this invention and in which—

35 Figure 1 is a view partly in elevation and partly in vertical section of a portion of an exhaust nozzle having this improvement applied thereto.

40 Fig. 2 is a top plan view.

45 Fig. 3 is a plan view of a detail.

50 Fig. 4 is an enlarged vertical sectional view of one of the controlling members.

55 Referring more particularly to the drawing the numeral 10, designates the exhaust nozzle which may be of any desired size and configuration and the upper extremity 11, of the nozzle is reduced on its inner face as at 12, to provide a circumferential en-

largement at the upper end of the nozzle and which enlargement may be of any desired diameter and depth.

60 The nozzle is provided at any suitable point with horizontal bearings 13—14, the inner diameter of the bearing 13, being preferably larger than the inner diameter of the bearing 14.

65 Arranged within these bearings 13—14, and extending across the nozzle is a supporting element designated generally by the reference numeral 15, which is preferably in the form of a bolt having a head 16, and a threaded extremity 17. The portion 18, 70 of the element 15, adjacent the head is of a diameter somewhat larger than the diameter of the portion 19, constituting the threaded extremity, so that the element 15, may be placed in the bearings 13—14, by passing the 75 extremity 19, through the bearing 13. The element 15, is also provided with an enlarged portion 20, intermediate its ends which is also adapted to pass through the bearing 13. The portion 20, is provided 80 with an opening 21, therethrough for a purpose to be hereinafter set forth and the element is held against displacement by means of the head 16, abutting the bearing 13, and a nut or collar 22, which is threaded upon 85 the other extremity of the element 15, abuts the bearing 14.

86 An upright 23, having a shoulder 24, is supported by the element 15, and to that end the extremity 25, of the upright passes 90 through the opening 21, and is secured in position by means of a nut or collar 26, threaded upon the extremity 25, below the element 15, so as to hold the collar 24, against the element and the nut 26, may be 95 held against rotation with respect to the upright by means of a suitable fastening pin 27.

96 This upright 23, may be of any desired size and height and is held in its upright position preferably by locking the element 15, against rotation in its bearings, in any suitable manner such as by means of a locking pin 28 passing through the head 16, and into a suitable recess in the bearing 13.

100 Loosely mounted upon the upright 23, is an inverted substantially cone shaped element 29, the larger portion of the element 29, being of a diameter somewhat smaller than the internal diameter of the nozzle 10, so as 110 to provide an annular space 30, between the element 29, and the wall of the nozzle at the

extremity thereof. The lower extremity of the element 29, is adapted to rest upon the collar 24, and the element 29, is of such a diameter that the action or pressure of the 5 exhaust steam through the nozzle will cause the element 29 to rise and fall upon the upright 23 as the pressure or action of the steam thereon varies.

In order to limit the movement of the element 29 under the influence of the steam pressure thereupon there may be provided 10 a stop device 31, preferably in the form of a pin which extends through the upright 23, and projects therebeyond. This stop 31, is 15 disposed at any desired point above the element 29, when the latter is resting upon the collar 24. It will be manifest that when the steam operates upon the element 29, the rising movement of the element will be limited 20 by the stop 31. As the element 29, rises the size of the annular opening 30, will be varied inasmuch as the upper extremity of the element 29, when the latter rests upon the collar 24, stands substantially flush with the 25 base of the enlarged portion 12, at the tip of the nozzle, but when the element 29, rises the upper end thereof will be moved above the base of the enlarged portion 12, and as the element 29, moves in an upright direction, the size of the annular opening 30, will 30 be enlarged. As the pressure increases or decreases this element 29, will rise and fall automatically and through the rising and falling movement of the element the velocity of the exhaust steam out of the nozzle 35 is automatically varied to control the draft on the fire, which is accomplished by varying the size of the annular opening as just described.

40 In order to vary the pressure at which the element 29, will be operated, any suitable means may be provided such as a plurality of supplemental elements or weights 32-33, which are adapted to be placed upon the upright 23, and superposed upon the element 29.

The lowermost weight 32, is preferably provided with a downwardly opening recess 34, preferably of a diameter slightly greater 50 than the diameter of the opening 35, through which the upright 23 passes and this element 32, is also provided with a recessed portion 36, into which the pin or stop 31, projects, the two cooperating to hold the element 32, 55 against lateral displacement with respect to the upright 23, and the element 29.

With this improved construction it will be manifest that the operation of the element 29, will be automatic and through this automatic operation of the element, controlled 60 entirely by the pressure of the exhaust steam thereupon, the velocity of the exhaust steam out of the nozzle will be automatically regulated and this in turn will automatically control the draft on the fire.

Obviously any number of the element 32-33, may be provided as desired.

While the preferred form of the invention has been herein shown and described, it is to be understood that various changes may be made in the details of construction, and in the combination and arrangement of the several parts, within the scope of the claims, without departing from the spirit of this invention.

75 What is claimed as new is:

1. A constantly open exhaust nozzle for locomotive engines, a floating element operable automatically by the action of the steam thereupon to vary the exhaust blast from 80 the nozzle, the external diameter of the element at all points being considerably less than the internal diameter of the nozzle, and means maintaining the element entirely 85 within the nozzle.

2. A constantly open exhaust nozzle for locomotive engines, a floating element operable automatically by the action of the steam thereupon to vary the exhaust blast from 90 the nozzle, the external diameter of said element at all points being considerably less than the internal diameter of the nozzle, means for causing the movement of the element to be in a direction lengthwise of the nozzle, and means maintaining the element 95 entirely within the nozzle.

3. A constantly open exhaust nozzle for locomotive engines, a floating element operable automatically by the action of steam thereupon to vary the exhaust blast from 100 the nozzle, the external diameter of the element at all points being considerably less than the internal diameter of the nozzle, means whereby the weight of the said element may be varied at will, and means maintaining the element entirely within the nozzle.

4. A constantly open exhaust nozzle for locomotive engines, a floating element operable automatically by the action of the steam 110 thereupon to vary the exhaust blast from the nozzle, the external diameter of the element at all points being considerably less than the internal diameter of the nozzle, means whereby the weight of said element 115 may be varied at will, the said means embodying weights attachable to and detachable from the said element at will, and means maintaining the element entirely within the nozzle.

5. A constantly open exhaust nozzle for locomotive engines, a floating element operable automatically by the action of steam thereupon to vary the exhaust blast from 125 the nozzle, the external diameter of the element at all points being considerably less than the internal diameter of the nozzle, and means for limiting the movement of the said element in one direction under the influence of the steam, the said means main- 130

taining the element entirely within the nozzle.

6. A constantly open exhaust nozzle for locomotive engines, an inverted conically shaped floating element operable automatically by the action of the steam thereupon to vary the exhaust blast from the nozzle, the external diameter of the element at all points being considerably less than the in-

10 ternal diameter of the nozzle, the internal diameter of the nozzle adjacent the tip being greater than the diameter of the remaining portion of the nozzle, and means maintaining the element entirely within the

15 nozzle.

7. A constantly open exhaust nozzle for locomotive engines, an upright disposed centrally of the nozzle, a floating element freely and automatically movable upon the up- 20 right to vary the exhaust blast from the nozzle, the external diameter of the element at all points being less than the internal diameter of the nozzle, and means maintaining the element entirely within the nozzle.

25 8. A constantly open upright exhaust nozzle for locomotive engines, an upright disposed centrally of the nozzle, a floating element freely and automatically movable upon the upright to vary the exhaust blast from 30 the nozzle, the external diameter of the element at all points being less than the internal diameter of the nozzle, and a stop connected with the upright to limit the movement of said element in one direction, the 35 said stop operating to maintain the element entirely within the nozzle.

9. A constantly open exhaust nozzle for locomotive engines, a floating element operating automatically to vary the exhaust blast from the nozzle, the external diameter of 40 the element at all points being less than the internal diameter of the nozzle, and means maintaining the element entirely within the nozzle.

10. A constantly open exhaust nozzle for 45 locomotive engines, a floating element co-operating therewith and operating automatically to vary the size of the discharge outlet from the nozzle, the external diameter of the element at all points being con- 50 siderably less than the internal diameter of the nozzle, and means maintaining the element entirely within the nozzle.

11. A constantly open upright exhaust nozzle for locomotive engines, an upright 55 disposed centrally of the nozzle, a floating element freely and automatically movable upon the upright to vary the exhaust blast from the nozzle, the external diameter of the element at all points being considerably 60 less than the internal diameter of the nozzle, one or more weight elements adapted to be connected with the said floating element, the said weight elements being also mov- 65 able upon the upright and with the floating element, and means maintaining the element entirely within the nozzle.

In testimony whereof I have signed my name to this specification, on this 19th day of November, A. D. 1920.

JAMES TROTTER.
